DISPOSABLE CHUCK HANDLE FOR AN ELECTRO-SURGICAL KNIFE OR THE LIKE

John J. Valeska, Rochester, N.Y., assignor to Sybron Corporation, Rochester, N.Y., a corporation of New York

Filed Oct. 24, 1968, Ser. No. 14,157

Term of patent 7 years

Int. Cl. D24—03; D8—02
U.S. Cl. D83—12

FIG. 1

FIG. 2

FIG. 3

FIGURE 1 is a side elevational view of the disposable chuck handle for an electrosurgical knife or the like, the opposite side being a mirror image thereof;

FIGURE 2 is a top plan view thereof at an enlarged scale; and

FIGURE 3 is a bottom plan view thereof at an enlarged scale.

I claim:

The ornamental design for a disposable chuck handle for an electrosurgical knife or the like, substantially as shown and described.
